United States Patent Office

Des. 196,746
Patented Oct. 29, 1963

196,746

COMBINED STEAM AND SPRAY IRON

Burton Kelly, Bellwood, and John E. Reed, Glen Ellyn,
Ill., assignors to Sunbeam Corporation, Chicago, Ill.,
a corporation of Illinois

Filed July 6, 1962, Ser. No. 70,820

Term of patent 14 years

(Cl. D49—6)

FIG. 1 is a perspective view of a combined steam and spray iron showing our design;

FIG. 2 is a side elevation view thereof;

FIG. 3 is a top plan view thereof;

FIG. 4 is a front elevation view thereof; and

FIG. 5 is a rear elevation view thereof.

The dominant features of our design reside in the portions shown in full lines.

We claim:

The ornamental design for a combined steam and spray iron, as shown and described.
